DESIGN.

—o—
FOLDING BED CASE.

No. 16,851.

Patented Aug. 10,

UNITED STATES PATENT OFFICE.

CHARLES TEUFEL, OF CHICAGO, ILLINOIS.

DESIGN FOR A FOLDING-BED CASE.

SPECIFICATION forming part of Design No. 16,851, dated August 10, 1886.

Application filed May 29, 1886. Serial No. 203,658. Term of patent 7 years.

To all whom it may concern:

Be it known that I, CHARLES TEUFEL, residing at Chicago, in the county of Cook and State of Illinois, and a citizen of the United States, have invented and produced a new and original Design for Upright Folding-Bed Cases, of which the following is a full description, reference being had to the accompanying drawing, in which the figure is an elevation in perspective.

The design consists in the several ornamental features hereinafter fully specified, and particularly pointed out in the claim, whereby a neat and tasteful appearance is given to the front of the casing, as clearly shown in the accompanying illustration and pointed out in the claim.

a represents the sides of the movable portion of the case, the upper end of each side having the inset portion *b*, bounded below by a piece, *c*, and upon the inner side by the side piece, *d*, and having the space between *a* and *d* and above the piece *c* occupied by the ornamental panel *e*. Between the pieces *d*, on each side of the case, is a looking-glass, *f*. Below the pieces *c* the case is provided with any suitable ornamental panel, *g*, on each side, the same being preferably set out or in front of the plane of the mirror *f*. The lower portion,

h, of the case is projected outward in front of the plane of the panels *g*, and is made to represent any suitable ornamental paneling. Upon each side the casing *i* is placed a side piece having ornamental edges, as shown. Above the piece *b*, to the top or molding, is filled with a panel, *e*, and between the intermediate pieces, *d*, is placed a looking-glass, *f*, or other panel. The front *g*, below the case *e*, may be paneled off in any desired form, and, as shown, the base *h* is projected out from the panel portion *g*. The case as a whole is located in a stationary case, *i*. The indented portion formed by the parts *b c d*, with the back or panel *e*, breaks the continuity of the front of the case and presents to the eye, when viewed, a very pleasing and effective contour.

I claim—

The design for an upright bed-case, consisting of the inset portions upon each side at the top of the case, each having an ornamental panel, *e*, the intermediate mirror, and the side panels, *g*, set out relatively to the inset portions substantially as described and shown.

CHAS. TEUFEL.
